EUGENE H. LANSING, OF WATERFORD, NEW YORK

FELT CLEANING APPARATUS

Application filed April 4, 1929. Serial No. 352,581.

This invention relates to an improvement in cleaning apparatus for paper making felts wherein water or other cleaning fluid is delivered onto the surface of the felt and the 5 water and dislodged impurities are removed from the felt by suction boxes.

In an apparatus of this character, it has been found that the suction influence of the suction boxes is not as completely effective on 10 the felt as might be and that for various reasons the cleaning incident to the suction is not in proportion to the suction. For example, at points in the cleaning operation, the suction is more or less effective beyond and above the 15 surface of the felt, thus tending to draw particles of dust in the air into the body of the felt and in a measure tend to increase the refuse particles in rather than remove them from the felt. Furthermore, it is customary 20 to use a roller in the suction opening of the suction box to prevent the felt being drawn inwardly over the edges of the opening by the suction. This roller, while admirably serving the purpose of preventing the felt from 25 being drawn inwardly toward the box, has a natural tendency to prevent that intimate contact between the lower surface of the felt and the surface of the box necessary to the best suction effect.

30 The primary object of the present invention is the provision of means, flexible in itself and adapted to move with the suction box, to overlie and bear upon the felt throughout that portion of the felt at least which may 35 be overlying the suction opening, this element serving to insure intimate contact between the felt and face of the suction box and preventing any material influence of the suction on the air above the felt.

40 Structurally considered, the improvement comprises a pressure contactor in the form of an endless flexible element which overlies and contacts with the felt and is in itself at all times in movement in response to the movement of the felt, the contactor overlying and bearing on the felt throughout an area which is subjected to the suction influence, the contactor moving with the suction box to maintain its relation with said box in insuring the 45 pressure contact on that portion of the felt

with which the suction opening cooperates in all and every position of the suction box.

The invention is illustrated in the accompanying drawings, in which :

Figure 1 is a vertical section, partly in elevation, showing the improved cleaning apparatus in cooperation with a felt. 55

Figure 2 is a perspective view of the spray heads forming part of the cleaning apparatus and illustrating more particularly the pressure contactors and their connection with the spray heads. 60

Figure 3 is a transverse sectional view through the cleaning apparatus illustrating the relation of the parts. 65

Figure 4 is a perspective view showing a modified form of contactor and suction box. 70

The cleaning apparatus involving the spray heads, suction boxes and the parts for insuring correlative operation of the parts is described more particularly in my co-pending application filed April 4, 1929, Serial No. 352,580. For the purposes of the present disclosure, these details may be briefly described as follows: 75

The usual felt 1 is mounted for longitudinal movement between side frame bars 2. These bars support a threaded shaft 3 above and transversely of the felt, concentric with which is arranged a hollow guide 4 terminally secured in the side bars 2 and having a longitudinally ranging slot 5 in its upper portion. The spray heads 6 are mounted for sliding cooperation with the guide, each including a hollow chamber 7 overlying and bearing on 80 the guide and a traveler 8 connected to the chamber by a web 9 extending through the slot 5, the traveler being formed with a threaded opening 10 to cooperate with the shaft 3. A spray nozzle or jet 11 communicates with the chamber 7, and two such spray heads are held in relatively fixed relation by a pipe connection 12 which is in open communication with the respective chambers 7 and is served with cleaning fluid from any 85 suitable source. The spray heads are spaced apart transversely of the felt a distance at least equal to half the width of the felt.

Suction boxes 13 are arranged beneath the felt immediately in advance of the respective 90 95 100

spray heads, there being one such suction box in alignment longitudinally of the felt with each spray head, the suction boxes being held in rigid spaced relation by a guide rod 14.

5 The suction boxes are formed below the suction chamber with interiorly threaded openings 15 to cooperate with a threaded shaft 16 mounted in the frame bars 2. Suitable mechanism, indicated generally at 17, involving appropriate gears and pinions and a clutch member 18 is arranged to compel reciprocating movement of the spray heads and suction boxes, the shifting of the clutch being automatically controlled by a lever 19, a rod 20 connected to the lever and adapted to be moved through the engagement of one of the suction boxes with a projection 21 on said rod to thereby move the clutch in one direction, the lever under such movement being held by 25 a latch 22 which is tripped by the other suction box at the opposite limit of movement of such boxes, to thereby release the lever to the influence of a spring 23 which shifts the clutch for an opposite cooperation.

25 By this construction, the spray heads and suction boxes are reciprocated transversely of the felt, so that the entire area of the felt is first subjected to the action of the cleaning fluid from the spray nozzles or jets 11 and 30 then to the action of the suction boxes as the wetted portion of the felt advances.

Each suction box 13 is provided with a face plate 24 upon which the felt 1 rests, this face plate being formed with a narrow slot 25 of a 35 length less than the similar dimension of the face plate and the major dimension of the slot extending transversely of the felt. The suction chamber 26 of the suction box is in communication through a flexible conduit 27 with any appropriate source of power tending 40 to exhaust the air from the suction space.

It has been found by experience that there is a tendency to draw the felt inwardly by the suction, so that there is more or less of a 45 rubbing action against the edges of the slot 25 and the felt. To overcome this, it has been proposed to mount a roller 28 in bearings 29 secured to the under side of the face plate 24, with the periphery of the roller substantially 50 in the plane of the upper surface of the face plate and the diameter of the roller less than that of the slot 25. The felt is thus supported at a point longitudinally of and between the edges of the slot 25 to prevent the felt being 55 drawn inwardly by the suction while at the same time affording ample space for the ingress of water and other material removed from the felt by the suction.

With the suction boxes constructed as described, it has been found difficult to maintain an intimate and substantially sealing contact between the felt and the upper surface of the suction box immediately adjacent the edges of the opening, and furthermore it has been 60 found that a suction sufficient to clean the

felt of the contained water and impurities to the desired degree will at times extend its influence beyond the upper surface of the felt and thus draw into the felt any floating particles which may exist in the air immediately 70 above the felt. Both of these objectionable influences are highly disadvantageous in felt cleaning, for the first tends to an imperfect suction action on the felt and the second tends to adding to the impurities in the felt. 75

The primary object of the present invention is to overcome both of these defects by providing for movement with the spray heads and suction boxes, pressure contactors which will insure intimate contact between the felt and suction box adjacent the slot and will also prevent suction effect on the air above the upper surface of the felt. 80

These pressure contactors are indicated in their preferred form in Figure 2 and comprise endless webs 30 of appropriate comparatively heavy textile material freely supported on rods 31 carried in the lower end of hanger straps 32, the upper ends of which are pivotally connected at 33 to the opposing 85 side walls of one end of the chamber 7 of each spray head. The pressure contactors 30 extend toward and are of such length as to project beyond the slot 25 in the immediately advanced suction box, the width of the contactor being somewhat greater than the length of the slot 25. Thus, each contactor extends from one of the spray heads, being supported at one end by a spray head and its 90 opposite end resting freely on the felt beyond the slot in the particular aligned suction box. As the contactor is flexible and endless, that is in tube-like form, it is apparent that the contactor rests for the greater portion of its length directly on the surface 95 of the felt and that as the felt is moving in the direction of the free end of the contactor, the movement of the felt will insure a corresponding movement of the contactors, causing same to move continuously around their 100 supporting rods 31. As the contactor moves with the spray heads, and as the suction boxes are maintained in fixed relation to the spray heads, it is apparent that the contactors will move transversely across the felt and at 105 the same time have an independent endless movement around the supporting rods 31 in the direction of movement of the felt. The pressure of the contactors on the left insures 110 that the felt throughout the area of and beyond the edges of the slot 25 in each suction box will be pressed into more or less intimate contact with the face plate 24 of the suction box to insure the most effective action of the 115 suction. Furthermore, as the contactor superimposes two layers of material above the felt, it is apparent that the suction effect beyond and above the surface of the felt is very 120 materially reduced and any tendency of such suction to draw air-carried particles toward 125

130

the felt will simply move the particles into the surface of the contactor. It is contemplated, however, that the thickness and texture of the contactor is such as to practically negative any suction effect above the contactor.

In Figure 4 there is shown a slight modification wherein the contactor is adapted for use with the conventional type of suction box 10 which is designed to be fixed with respect to the frame and extend transversely of and throughout the width of the felt. Here the suction box 34 underlies the felt 35 and is supported by a rod 36 mounted in the side 15 bars of the frame. The slot 37 of the suction box is substantially coextensive with the width of the felt. The contactor, indicated at 38, is similar to the contactor previously described except in relation to its width; that 20 is to say, the contactor is of endless form and of a length to bear upon the felt, at least throughout an area coextensive with that of the slot 37. The contactor is supported upon a rod 39 supported in hangers 40 which are 25 connected to the frame structure above the felt. In this form, the contactor is without movement transverse the felt but serves its full function and of course is capable of movement under the influence of the moving 30 felt, as in the preferred form.

What is claimed to be new is:

1. The combination with a paper making felt and a slotted suction box underlying the felt, of a flexible pressure contactor overlying 35 the felt and presenting a constantly changing surface thereto, said contactor serving to exert pressure on the felt throughout the area of the slot in the suction box.

2. The combination with a paper making 40 felt and a slotted suction box underlying the felt, of a flexible pressure contactor overlying the felt and serving to exert pressure on the felt throughout the area of the slot in the suction box, said contactor being of endless 45 form and independently movable by and through contact with the moving felt.

3. The combination with a moving paper 50 making felt and a slotted suction box beneath the same, of a pressure contactor of endless form supported at one end above the felt, said contactor for a material portion of its length 55 resting upon the felt in that portion overlying the slot of the suction box.

4. A paper making felt cleaning apparatus 60 including spray heads movable transversely of the felt, suction boxes movable with the spray heads, and a flexible pressure contactor carried by and movable with each spray head, said contactor resting on the felt above the ad-

said contactor resting on the felt above the suction box and being of endless form and independently movable by and with the moving felt.

6. A cleaning apparatus for paper making 70 felts, including spray heads movable transversely of the felt, suction boxes movable transversely of the felt, hanger bars depending from each spray head, a rod connecting the hanger bars of each spray head, and a pressure contactor of endless form encircling the rods, said pressure contactor in advance of the spray heads resting upon the felt above the suction boxes.

7. A cleaning apparatus for paper making 80 felts, including spray heads movable transversely of the felt, suction boxes movable transversely of the felt, hanger bars depending from each spray head, a rod connecting the hanger bars of each spray head, and a pressure contactor of endless form encircling the rods, said pressure contactor in rear of the spray heads resting upon the felt above the suction boxes and moving over the rods responsive to the movement of the felt. 90

8. A paper making felt cleaning apparatus, including spray heads movable transversely of and above the felt, suction boxes movable in conjunction with said spray heads 95 transversely of and below the felt, and flexible pressure contactors connected with the spray heads so as to move therewith, and having free portions bearing upon the top of the felt above said suction boxes.

In testimony whereof I affix my signature. 100
